Specification for Design.

Patented Apr. 9, 1912.

Application filed January 26, 1912. Serial No. 673,700. Term of patent 14 years.

To all whom it may concern:

Be it known that I, GEORGE C. GEBELEIN, a citizen of the United States, residing at Wellesley, in the county of Norfolk and Commonwealth of Massachusetts, have invented a new, original, and ornamental Design for a Paper-Weight and Pen-Rest, of which the following is a specification, referring, being had to the accompanying drawing, forming part thereof.

The figure is a view in elevation of a paper-weight and pen-rest, showing my new design.

I claim:

The ornamental design for a paper-weight and pen-rest, as shown.

In testimony whereof, I affix my signature, in the presence of two witnesses.

GEORGE C. GEBELEIN. [L.S.]
